SWAGING APPARATUS

John C. Luley, Teaneck, N. J., assignor to Western Electric Company, Incorporated, New York, N. Y., a corporation of New York

Application April 2, 1946, Serial No. 659,815

5 Claims. (Cl. 153—9)

1

This invention relates to a swaging apparatus, and more particularly to apparatus for swaging containers on bases or covers for electrical units.

In the manufacture of communication equipment, numerous electrical units are housed in metal containers which initially have open ends to receive bases or covers for the containers, the bases supporting terminals for electrical connections with the internal parts of the units. In the present embodiment, a metal container is to be secured to a base, a portion of which supports coils and extends into the container while terminals are supported by the external portion of the base, supports terminals which form connection with the coils. The internal portion of the base and coils disposed in the container is to be embedded in a sealing compound, but before this takes place, the container must be secured to the base. Due to the particular structure of the base, the conventional methods of connecting the covers to containers cannot be employed.

An object of the invention is to provide an apparatus which is automatic in operation and highly efficient in connecting containers to supporting bases, of electrical units or the like.

Broadly, the invention comprises an apparatus for connecting a cylindrical article to a base having an annular groove therein, the apparatus including a swaging tool which is moved toward the base to force portions of the article into the annular groove during relative rotation of the tool and the article and base.

More specifically, the apparatus includes a swaging unit in which a support is provided for the grooved base and the cylindrical article or metal container when disposed on the base. A socket is movable downwardly under fluid operated means to extend over the upper end of the article and form a driving connection therewith. Power means is operatively connected to both the socket and the support to drive them in synchronism in the same direction about a common axis so that the article and base will be rotated in the same manner. During the rotary movement of the article and base, swaging rollers equally spaced about the support are forced inwardly simultaneously under like pressures to swage a portion of the article into the groove of the base. Upon the closing of the start switch, the apparatus is automatic in its operation through each complete operating cycle after which it resets itself for the next operation.

Other objects and advantages will be apparent from the following detailed description when

2

considered in conjunction with the accompanying drawings, wherein

Fig. 1 is a vertical sectional view of the apparatus;

Fig. 2 is a front elevational view of the apparatus with a portion of the cover removed;

Fig. 3 is an enlarged horizontal sectional view of the swaging unit, this view being taken along the line 3—3 of Fig. 1;

Fig. 4 is a vertical sectional view of the swaging unit, this view being taken substantially along the line 4—4 of Fig. 3;

Fig. 5 is a fragmentary sectional view taken substantially along the line 5—5 of Fig. 1;

Fig. 6 is a fragmentary detailed view of the structure shown in Fig. 5;

Fig. 7 is a diagrammatic illustration of the electrical and pneumatic control circuits for the apparatus;

Fig. 8 is a schematic illustration of the power driving mechanism; and

Fig. 9 is an enlarged detailed sectional view of the article and base in the swaging unit.

Referring now to the drawings, a supporting

frame 10 has a swaging or rolling unit 11 mounted thereon, the swaging unit being shown in detail in Figs. 3 and 4. A bottom plate 14 of the unit 11 is centrally apertured to receive a bearing 15 for a shaft 16. The shaft 16 carries a support 17 which is recessed at 18 to receive terminal portions 19 of a base 20. As shown in Fig. 9, the base 20 has an annular groove 21 therein and an integral flange 22 to support an article 23 which in the present embodiment is a cylindrical metal container. An upwardly projecting central portion 24 of the support 17 actually supports the base and article, its upper end being formed to engage and drive the base 20 when the support is rotated.

40 A plurality of cylinders 27 are mounted at equally spaced positions on the plate 14, the outer ends of the cylinders having passageways 28 which communicate with passageways 29 in the plate 14 and through these passageways to a fluid supply line 30. Pistons 32, disposed in the cylinders 27 and having projections 33 at their inner ends to space them from the inner ends of their cylinders function to force swaging rollers 35 inwardly simultaneously under like pressures

45 to force the material of the article into the recess of the base. The swaging rollers 35 have integral annular beads 36, lying in a plane with the groove 21 of the base. The swaging rollers are rotatably supported on like arms of bell-crank 50 levers 37, the adjacent arms of the levers having

rounded projections 38 to engage the outer ends of their respective pistons 32. The levers 31 are pivotally supported intermediate their ends on shafts 39 and are normally urged clockwise to force the swaging rollers away from the article and base and to force their pistons inwardly by force of springs 40 carried by their respective cylinders 27. A cover 41 is provided for the swaging unit 11 and is centrally apertured to receive the base and article.

The shaft 16, which carries the support 17, has its lower end journalled in a bearing 43, a gear 44 being mounted upon the shaft between the bearings 15 and 43. The gear 44 and its lower bearing 43 are disposed in a housing portion 45 of the frame 10 together with an intermediate gear 46 and a drive gear 47. The gear 46 is rotatably supported on a stub shaft 48 while the gear 47 is mounted upon the lower end of a vertical shaft 49. The shaft 49 is supported by bearings 50 adjacent its ends, a gear 51 being mounted upon the upper end of the shaft. The gear 51 is of the same size as the gear 47 and an intermediate gear 52, identical with the gear 46, operatively connects the gear 51 with a gear 53 which is identical with the gear 44. Through this train of gears, the base 20 and the article 23 are rotated simultaneously in the same direction and at the same speed about a common axis. The gears 52 and 53 are supported between a head plate 55 of the frame 10 and a bracket 54 mounted upon the head plate. A spindle 56 extends through the bracket 54, the gear 53 and the head plate 55 to support a socket 57 on the lower end thereof. The socket is hollow and open at its lower end to extend over the upper end of the article 23. A notch 58 in the socket 57 will receive a pressed-out portion 59 of the article (Fig. 2) to form a positive driving connection between the socket and the article.

The spindle 56 has its upper end mounted in a chuck 60 which is supported by a friction clutch 61 at the lower end of the conventional splined shaft 63, common in drill presses. The shaft 63 extends upwardly into a head structure 64 which houses a pulley 65 operatively connected to a pulley 66 of a motor 67 by a belt 68. The detailed structure of the head 64 is not shown, it being understood that the splined shaft 63 is rotated in the direction of the arrow (Fig. 8) and may be moved axially into and out of engagement with the article 23. The head 64 is supported by a bracket 70 mounted on a column 71, the bracket 70 carrying a support 72 for the motor 67. The column 71 has its lower end mounted in the frame 10 and is supported thereby.

Returning now to the gear 52 (Figs. 1 and 8), this gear is mounted upon the lower end of a shaft 73 which is the input shaft of a one revolution clutch unit 75. The train of gears in the unit 75 are shown in Fig. 8 connecting the input shaft 73 to an output shaft 76 of the unit. A connecting member 77 mounted upon the outer end of the output shaft 76, includes a notch 78 to receive a finger 79 (Figs. 5 and 6) of a controlling element 80. This portion of the clutch mechanism also includes a cam member 81 (Figs. 7 and 8) positioned to open a normally closed switch 82. The element 80 is pivotally supported at 84 and carries a gear segment 85 at its upper end to interengage a pinion 86. The pinion 86 is mounted upon a shaft 87 which carries a pinion 88 positioned in engagement with a rack 89 of a sleeve 90 which moves axially with the splined shaft 63.

A cylinder 93 supported by the bracket 70 contains a piston (not shown) connected to a rod 94 extending through and fixed to the adjacent end 96 of a bracket 97, the lower end of the rod carrying a plunger 98. The bracket 97 is connected to the splined shaft 63 to cause axial movement thereof downwardly during like movement of the piston and its ram or rod 94. In a similar manner, the shaft 63 is moved upwardly during the return movement of the piston in the cylinder to its upward position. When the splined shaft 63 is lowered sufficiently to lower the socket 57 over the article 23, and form connection therewith between the projection 59 and the slot 58 and close the friction clutch 61, the plunger 98 has been lowered sufficiently to open a normally closed valve 100.

Attention is now directed to the electrical and pneumatic control circuits shown in Fig. 7. The supply lines 102 and 103 for the electrical circuit 104 are connected to a suitable source of electrical energy. There is but one control switch 105 actuated by the operator to start the apparatus. When this switch is closed, a circuit is completed from line 102 through the switch 105 through switch 82, winding 106 of a relay 107 to line 103. Energization of the relay 107 will close its contacts 108, 109 and 110 completing a locking circuit for the winding 106 from line 102, through closed contact 110, switch 82, winding 106 to line 102. At the same time, a winding 112 of a solenoid operable valve 114 will be energized through the closing of a circuit from line 102, through closed contact 108, winding 112, closed contact 109 to line 103. Energization of the solenoid valve 114 will open a fluid line from a supply line 116, through a shut-off valve 117, a strainer 118, a pressure control valve 120 with its gage 121, line 115, valve 114 and through line 122 to a valve 123. In the present embodiment, the fluid employed is air under pressure. The movable element (not shown) of the valve 123, normally urged to the right by a spring 124, is moved to the left by air under pressure from line 122 when the valve 114 is opened. When in the operated (left) position the valve 123 opens a line 125 from the supply, through the valve and line 126 to the top of the cylinder 93. The piston in the cylinder is moved downwardly and at the same time, air beneath the piston is exhausted through line 127, the valve 123, line 128 and an exhaust muffler 129. When the plunger 98 operates the valve 100 a line is completed from the supply at connection 130, through line 131, a pressure control valve 132 with its gage 133, a strainer 134, valve 100 and line 30 to the cylinders 27 of the swaging or rolling unit 11. De-energization of the winding 112 will effect closing of the valve 114, freeing the valve 123 to return to its normal (right) position by its spring 124. Shifting of the valve 123 to its normal position connects line 125 with line 127 to direct air under pressure to the bottom of the cylinder 93 and at the same time, connects line 126 to line 128 to exhaust the air above the piston through the muffler 129. When the valve 100 is free to return to its closed position, it closes line 131 and opens line 30 to the exhaust muffler 129 through line 135.

Considering now the operation of the apparatus, it should be understood that the first action required of the operator is the locating of the base 20, with the cover or article 23 placed thereon, on the support 17 as illustrated in Fig. 4. A central aperture in the cover 41 assists the

operator in performing this function. The next action by the operator is the closing of the switch 105. The apparatus will then go through one complete cycle and reset itself for the next cycle of operation at which time the finished product may be removed from the apparatus and another base and article disposed in place.

After the base 20, with the article or container 23 thereon, is located on the support 17 and the operator closes the switch 105, the relay 107 is energized and is constantly under the control of the cam 81 of the one revolution clutch 75. When the contacts of the relay 106 are closed, the solenoid valve 114 is opened, operating valve 123, causing downward movement of the piston in the air cylinder 93, moving the splined shaft 63 and sleeve 90 downwardly with the clutch 61, the spindle 56 and the socket 57. During this interval of time, the motor 67 is energized, driving the shaft 63, but the support 17 and the socket 57 are not driven at this time as the clutch 61 is not engaged. When the socket 57 is moved downwardly over the upper end of the article and connection is completed between the notch 58 and the portion 79 (Fig. 2) further downward movement of the shaft 63 will engage the clutch 61 to drive the article in one direction and through gears 53, 52, 51, 47, 46 and 44, rotate the base in the same direction and at the same speed. The connection of the clutch 61 starts operation of the one revolution clutch 75 and rotation of its cam 81, the clutch 75 having been unlocked. During downward movement of the shaft 63 and sleeve 90, the element 80 is moved from its solid line position (Fig. 6) to its dot-dash position to free the one-revolution clutch for operation. As soon as connection is formed between the socket 57 and the article 23, the valve 100 is opened, opening the fluid lines to the cylinders 27 of the swaging unit, causing the pistons 32 to move inwardly, that is, toward the center of the unit. In this manner, all swaging rollers being moved by the same driving force, equal pressures will be applied at equally spaced positions about the article to roll the metal of the article into the groove 21 of the base. During this time, both the base and the article are positively driven, the swaging rollers being free to rotate upon their shafts to cause an easy flowing of the material of the article into the groove. When there has been one revolution of the clutch 75, during several revolutions of the socket 57 and support 17, the cam 61 will open the switch 82 deenergizing the relay 107 and also the winding 112 of the solenoid valve 114. When this occurs, the movable element of the valve 114 will return to its normal position under the force of a spring 124 (Figs. 1 and 7) reversing action of the piston in the cylinder 93 causing upward movement of the piston with its rod 94 and plunger 98. Upon the first upward movement of the piston rod, the valve 100 will be allowed to close exhausting the air back of the pistons 32 in the swaging unit and exhausting the air from the top of the cylinder through the muffler 129. During the first portion of the upward movement of the piston in the cylinder 93, the sleeve 90 and the shaft 63, the clutch 61 is disengaged stopping operation of the one-revolution clutch 75. Further movement of the sleeve 90 will rotate the pinion 89, its shaft 87 and pinion 86 to move the gear segment 85 and the element 30, to move the projection 79 into the notch 78 of the connecting member 11. The one-revolution clutch is thus locked against further

movement until released for the next operation near the bottom of the next downward stroke of the sleeve 90. In this manner, the apparatus is at rest, ready for the next operating cycle.

5 Although specific improvements of the invention have been shown and described, it will be understood that they are but illustrative and that various modifications may be made therein without departing from the scope and spirit of this 10 invention as defined by the appended claims.

What is claimed is:

1. An apparatus for connecting a cylindrical article to a base having an annular groove therein, the apparatus comprising a swaging tool, respective holders for the article and base, driving means to rotate the holder for the article to drive the article in a given direction and at a predetermined speed, driving means for the holder for the base operable in synchronism with the first driving means to drive the base in the same direction and at the same speed, and means to move the tool toward the base to force portions of the article into the groove of the base. 15 20 25

2. An apparatus for connecting a cylindrical article to a base having an annular groove therein, the apparatus comprising a plurality of swaging rollers equally spaced about the base and having their peripheries disposed in general alignment with the groove of the base, means to 30 individually support the rollers for movement toward and away from the base, separate means normally urging the roller away from the base, means to rotate the article and base, and fluid operated means to simultaneously force the 35 rollers under like pressures toward the base during rotation of the article and base to cause swaging of a portion of the article into the groove of the base.

3. An apparatus for connecting a cylindrical 40 article to a base having an annular groove therein, the apparatus comprising a rotatable member to support and rotate the base, a reciprocable and rotatable element to rotate the article, a unit operatively connecting the member and element 45 to cause rotation of the member simultaneously with the element about a common axis and in the same direction with the element when the element is rotated, a driving shaft to move the element into and out of engagement with the 50 article, means interposed between the driving member and the element to operatively connect them after the element has engaged the article, and means to move the swaging tool during rotation of the article and base to force material of 55 the article into the groove of the base.

4. An apparatus for connecting a cylindrical article to a base having an annular groove therein, the apparatus comprising a rotatable member to support and rotate the base, a reciprocable 60 and rotatable element to rotate the article, a unit operatively connecting the member and element to cause rotation of the member simultaneously with the element about a common axis and in the same direction with the element when the element is rotated, a driving shaft to move the element into and out of engagement with the 65 article, means interposed between the driving member and the element to operatively connect them after the element has engaged the article, 70 means operable to lock the unit against operation until the element engages the article, and means to move the swaging tool during rotation of the article and base to force material of the article into the groove of the base.

5. An apparatus for connecting a cylindrical

article to a base having an annular groove therein, the apparatus comprising a rotatable member to support and rotate the base, a reciprocable and rotatable element to rotate the article, a unit operatively connecting the member and element to cause rotation of the member simultaneously with the element about a common axis and in the same direction with the element when the element is rotated, a driving shaft to move the element into and out of engagement with the article, means interposed between the driving member and the element to operatively connect them after the element has engaged the article, means operable to lock the unit against operation until the element engages the article, means 15 movable with the driving shaft to operate the

locking means to control the time interval of operation of the unit, and means to move the swaging tool during rotation of the article and base to force material of the article into the groove of the base.
